FRED F. CONWILL, OF BERKELEY, CALIFORNIA.

APPARATUS FOR DECORATING.

Application filed November 9, 1925. Serial No. 67,908.

The general object of the present invention is to provide a simple, effective, expeditious and comparatively inexpensive apparatus for decorating interiors such as the walls and ceilings of rooms in a building.

The invention further proposes to simplify and improve the methods heretofore employed for tinting, stenciling and embossing effects; and still further proposes to accomplish certain combinations of these effects simultaneously upon the surface to be decorated.

The above and other objects are accomplished by instrumentalities pointed out in the following specification.

The invention is clearly defined in the claim.

A satisfactory embodiment of the invention is illustrated in the accompanying drawings forming part of the specification and in which—

Figure 1 is a front elevation of a fragment of a wall, showing the form of apparatus used in connection with the present invention.

Figure 2 is a side elevation of parts shown in Figure 1 with the wall in section.

Figure 3 is a vertical cross section of the apparatus shown in Figures 1 and 2, but on a slightly enlarged scale.

Figure 4 is a fragmentary cross section at right angles to Figure 3 and taken approximately on the line 4—4 of that figure.

Figure 5 is a detail cross section of the form of pattern used in connection with the present invention.

Figure 6 is a view similar to Figure 5 of another or modified form of pattern, and

Figure 7 is a fragmentary front elevation of a still further form of pattern.

In carrying out the present invention, use is made of a sheet 5 of absorbent material as, for instance, paper formed of vegetable fibre. This type of paper may be of the kind known as ordinary blotting paper or be a still cheaper grade such as is used in the manufacture of wall paper. The sheet 5 may be of any width found convenient for handling and in the dimension of its width may correspond approximately to the width of ordinary wall paper. I provide the sheet with a pattern. As shown in Figures 1 and 6 the pattern may be in the form of cut out portions 6 and 7 or, as shown in Figure 5, the pattern may take the form of a depre-

sion 8 or, in accordance with the modified form shown in Figure 7, the pattern 9 may be formed by rendering certain areas of the sheet 5 non-absorptive by the application thereto of a coating of shellac or other suitable material. Various patterns, of course, may be formed with any required outline and arranged in any preferred relation to one another. In using the pattern just described in accordance with the present method, the sheet 5 is superimposed upon an undried coating of any of the prevailing types of liquid coloring matter now employed for decorating walls and ceilings. In this application of the sheet 5, the areas thereof surrounding the patterns absorb and thereby displace the liquid substance of the coating so that when the sheet is removed from its position on the wall or ceiling, a contrast is had between those areas of the coating which were not in contact with the sheet by reason of the presence of the pattern and those areas from which portions of the coloring matter were absorbed by the sheet. It is thus obvious that contrast is produced in the colored coating on the surface of the wall by withdrawing or displacing the coloring matter from certain areas and leaving the coloring matter untouched in other areas. Heretofore stenciling was resorted to in most cases for producing contrast but stenciling involved the addition of one or more contrasting colors, whereas, the present method contemplates subtraction or removal of coloring matter as distinguished from the addition thereof.

Stippling too has heretofore been employed for modifying the tones of the ground color between the designs produced by stenciling. With the present invention it is obvious that a stippling effect can be produced simultaneously with the erection of the design by the pattern, it being obvious that when the sheet 5 is superimposed upon an undried coating with the application of relatively heavy pressure upon certain areas thereof and relatively light pressure on other portions, or continuously varying pressure will result in imparting not only a stippling effect to the coating of coloring matter but will also produce therein tonal effects.

A simple form of apparatus, shown in Figures 1 to 4 inclusive, may be employed for operating the sheet 5 in the manner just described. In this connection the sheet 5

is made relatively long, in fact, its length may correspond to the height of the wall or one of the lateral dimensions of a ceiling, to be decorated. As shown in Figures 1 to 3 inclusive, this sheet is wound upon a roller 10 which has trunnions 11 and 12 journaled in opposite side portions 13 and 14 of triangular shaped plates 15 which comprise a frame. The roller 10 is by preference disposed in one of the corner portions of the base of the frame and in alignment with a second roller 16 disposed in the apex portion of the frame and having trunnions 17 and 18 journaled in the side portions 13 and 14. The sheet 5 extends from roller 10 and is trained around a cylindrical brush 19 carried by a roller 20 whose ends are journaled in the side members 13 and 14 of the frame, the brush 19 being disposed in the corner portion of the base opposite to the roller 10. The sheet extends under the brush and therefrom is directed laterally and secured to the roller 16. The brush 19 is of a size to extend beyond the base of the frame so that the section of sheet 5 between roller 10 and brush 19 is caused to project beyond the edge of the base. In this way the presence of the base of the frame does not prevent the section of the sheet between the roller 10 and brush 19 from making contact with the wall or ceiling.

A handle 21 having a fork 22 at one end is formed integral with or otherwise connected at the end of the corner portions of the side members 13 and 14 adjacent to the roller 10. This handle 21 slopes outwardly so as to provide a clearance for the hand of the operator between the handle and the wall in the operation of the device. The trunnions 12 and 18 extend beyond the adjacent side member 13 of the frame and have secured thereto pulley sheaves 23 and 24 around which are trained an endless belt 25 which transmits motion from the roller 10 to the take-up roller 16.

In the operation of the device the sheet 5 as described is rolled upon the roller 10, then extended underneath brush 19 and connected to take-up roller 16. The operator then proceeds by pressing the section of the sheet between roller 10 and brush 19 to the surface of the wall or ceiling to which a coating of coloring matter has been applied and before the coating has dried. The application of the device is by preference initially made to the upper portion of a wall, and the device is manipulated so that the entire section between the roller 10 and brush 19 makes contact with the wall. The operator then proceeds to move the device vertically downward and in so doing the friction between the sheet and the wall, and due to the pressure applied to the frame by the hand of the operator, causes the sheet

to unwind from roller 10, whereupon take-up roller 16 is operated through belt 25 to wind the sheet as the same is unwound from roller 10.

It will be noted by reference to Figure 2 that pulley 23 is smaller than pulley 24 so that take-up roller 16 rotates at a higher rate of speed than roller 10. This difference in speed between the rollers prevents slack in the run or section between the brush and roller 10, and operates to maintain the sheet taut. It will, of course, be understood that provision is made by having the belt relatively loose to prevent the roller 16 from exerting a pull on the sheet that would operate to break the same. The employment of the brush 19 is ideal in connection with sheets provided with indentations, such as shown at 8, or with non-absorbent areas, as shown at 9, but in practice it has been found undesirable to use the brush when cut-out portions, such as 6, are used for patterns. When using a sheet, such as shown in Figure 1, provision is made to eliminate contact between the brush and the sheet by an adjustable plate 26 connected at one end to a transverse roller 27 which is adapted to be turned by having its ends mounted in the sides 13 and 14 of the frame. The free end of the plate is rounded by curving the same outwardly, as at 28, and the plate is adapted to occupy a position upwardly and away from the base and brush 19, or to be moved downwardly and outwardly and to a position tangentially of the brush, in which position the rounded end portion 28 extends well beyond the base of the frame and the brush, as shown by dotted lines in Figure 3. The dotted line position of the plate 26 permits the sheet to be trained around the curved portion 28 and the presence of the brush holds the plate in position under the pressure which is applied to the frame when the device is in use. In that the sheet of the present invention is relatively inexpensive to provide, it is proposed that after each use to discard the used sheet and replace with a fresh or new sheet. This practice, however, can be left to the discretion of the operator and will, of course, be governed by the absorptive qualities of the sheet and the character of coloring matter used.

Although I have shown and described one embodiment of my invention, it is to be understood that the same is susceptible of various changes; and I reserve the right to employ such as may come within the scope of the appended claim.

I claim:

A decorator's device comprising a rolled sheet of absorptive material adapted to be placed in contact with certain areas of an undried coating of liquid coloring material

upon the surface of a room and to be unrolled thereover and absorb the said material, said sheet being provided with a non-absorptive pattern adapted to isolate certain other areas of the coating from the absorptive action of the sheet in the unrolling of the sheet upon the coating, and means for

supporting said roll including a rotary brush for causing contact between the sheet and the surface being operated upon and means for re-rolling the sheet as the same is moved from the first named roll. 10
